UNITED STATES PATENT OFFICE

2,232,616

YARN CHANGER

Walter Larkin, Norristown, Pa., assignor to
Fidelity Machine Company, Wilmington, Del.,
a corporation of Delaware

Application July 31, 1940, Serial No. 348,901

29 Claims. (Cl. 66—144)

This invention relates to a yarn selecting device of the type disclosed in my prior United States Letters Patent No. 1,624,792, dated April 12, 1927, and No. 1,726,396, dated August 27, 1929.

5 In the devices of the two patents noted above, and in the present device, one yarn is selected from a group and tied end to end to another yarn of the group which at the time of the new selection is running freely from a cone, bobbin, 10 or other yarn package to the needles of a knitting machine, or to any other apparatus to which the selecting device is attached and in which the various yarns of the group are utilized.

As the knot between the running yarn and the 15 newly selected yarn is tied, the running yarn is severed at the knot. The newly selected yarn becomes the running yarn and passes freely to the needles etc., until the next yarn selection. As the knotting operation is being completed, and 20 the previous running yarn is severed at the knot, the free end of the former running yarn is gripped and held in position for subsequent selection of that particular yarn, and the previously gripped end of the newly selected yarn is released, in 25 order that the newly selected yarn may supplant the running yarn and pass freely from its supply package to the apparatus to which the device is attached.

In the devices of the prior patents noted above, 30 each yarn of the group was controlled by a separate rockable finger having an eye in its outer free end through which the yarn passed in going from its supply package to the clamp by which the ends of the idle yarns were gripped, or to 35 the needles of the knitting machine in the case of the running yarn. As the selection was made the finger controlling the selected yarn held it substantially straight and under tension between the clamp and the eye, across the path of a Y-shaped collecting lever rocking in a plane at right 40 angles to the parallel planes of the respective selector fingers. The yoke-shaped end of the collecting lever picked up the selected yarn and also the running yarn and carried the two to the beak and pinchers of the knotting device. 45 Here the two were tied together and the severed end of the running yarn placed in the clamp while the clamped end of the selected yarn was released therefrom. The selector finger and the 50 collecting lever then returned to their normal positions respectively, leaving the newly selected yarn running to the needles of the knitting machine through the eye of its control finger.

More recent developments in the knitting arts 55 have necessitated speeding up the knitting ma-

chine. This, in turn, necessitated quicker action of the yarn selecting device, including the collecting lever. As a result of the high speed operation, the collector lever had a tendency, at times, to throw the yarns out of the open yoke end thereof. Thus, the two yarns would not be properly presented to the knotter, which caused the operation of the knitting machine to be interrupted by the stop motion, when the two yarns separated at the defective knot resulting from the 10 improper presentation of the yarns to the knotter.

The present invention resides in a new and improved structure by which the aforesaid high speed difficulties are effectively avoided. In the improved selector device the separate collector 15 lever is eliminated and the mechanism reorganized in such a manner that each yarn-control lever maintains complete control of its own particular yarn at all times and functions additionally to pick up the running yarn and carry it and 20 the newly selected yarn to the knotter.

Other features of the new structure reside in its relative simplicity and positive positioning of the yarns at the clamp and at the knotter, as will be fully disclosed hereinafter, reference being had 25 to the accompanying drawings of which:

Figs. 1 and 1a constitute an elevation of one side of the improved yarn selector;

Fig. 2 is an elevation of the opposite side of the device;

Fig. 3 is a front elevation of the device;

Fig. 4 is a plan view of the assembled device;

Fig. 5 is a plan view with certain upper parts removed;

Fig. 6 is an enlarged sectional elevation of the 35 knotter, as taken on the line 6—6, Fig. 4;

Fig. 7 is a perspective view, partly in section, showing the operating mechanism for the individual yarn control fingers;

Fig. 8 is a detailed perspective view of the individual yarn control fingers and the mounting therefor;

Fig. 9 is a detached perspective view of the finger locking mechanism;

Fig. 10 is a sectional view illustrating the finger 45 operating gearing, as taken on the line 10—10, Fig. 7;

Fig. 11 is a perspective view illustrating the normal positions of the various parts, while one of the yarns is running freely to the needles of the knitting machine to which the device is attached;

Fig. 12 shows the relative positions of the parts after a selection has been made and the 50 yarn control finger for the selected yarn has 55

moved the selected yarn and the running yarn into the throat of the knotter;

Fig. 13 is a perspective view showing the beak of the knotter starting to tie a knot to secure the newly selected yarn to the running yarn;

Fig. 14 is a perspective view showing the beak of the knotter about to close to complete the knot and the open shears ready to sever the running yarn adjacent the knot;

Fig. 15 is a plan view, partly in section, showing the shears in full lines in the position corresponding to that of Fig. 14 and in broken lines after the shearing has been effected;

Fig. 16 is a plan view, partly in section, of the main clamp and a temporary clamp employed in connection therewith during the yarn knotting operation;

Fig. 17 is a plan view partly in section of a yarn pincher employed in addition to the clamps of Fig. 16, during the knot-tying operation;

Fig. 18 is a plan view partly in section of the certain parts of the knotting pincher of Fig. 17;

Figs. 19, 20 and 21 are perspective views of the parts of the knotting pincher of Figs. 17 and 18;

Figs. 22, 23, 24 and 25 are detached perspective views of the various parts of the main clamp;

Fig. 26 is a perspective view of the temporary clamp; and

Fig. 27 is a side view of a detail of the mechanism shown in Fig. 1.

As shown in Figs. 1, 2, 3, 4, 5, 7 and 8, the present device comprises a plurality or group of yarn control fingers A, of which there may be any desired number depending upon the use for which the device is designed. In the present illustration, there are five yarn-control fingers, indicated at 1, 2, 3, 4 and 5 respectively, to provide what is known in the art as a "five-color striping attachment" for use with a circular knitting machine of the kind disclosed in the aforesaid prior patents, which show a "four-color striper."

As shown in Figs. 7, 8 and 10, each of the yarn-control fingers of the group A includes a disc-like hub portion 6 and an arcuate arm portion 7 formed integral therewith. At the rear of each finger, where the arm portion joins the hub portion, is a concave recess 8, for purposes hereinafter described. Each finger is preferably punched from flat sheet metal, although die or other light castings may be used.

The free end of each finger, i. e., the end opposite to the hub disc 6, is bent into a plane at 90° to that of the disc 6, as indicated at 9. The transversely extending terminal edge of the twisted head 9, in each instance, is provided with a collector notch 10 (see Fig. 1 particularly). Immediately behind and substantially aligned with the notch 10, each finger is provided with a yarn guide eye 11 for passage therethrough of the particular yarn which is to be controlled by the particular finger in which the eye is formed.

Intermediate the hub disc 6 and the head 9 of each finger, a barb-like projection 12 is bent laterally out of the plane of the main arm and disc portions of the finger, to form an open yarn-guiding notch 13 for the yarn controlled by the finger (see Fig. 12).

In each instance, as shown in Fig. 8, a partial gear 14 is secured, as by rivets 15 (see Fig. 10), to and against one side of the hub disc 6, with the teeth of the gear exposed in the concave recess 8. Each gear 14 and its associated hub

disc 6 are bored and bushed to receive and to rock freely on a common pivot rod 16, upon which the entire group A of fingers 1, 2, 3, 4 and 5 are mounted in closely laterally abutting relation to each other.

Secured to the extreme outer end of the pivot rod or stud 16 is a yarn guide bracket 17 having a portion 18 extending parallel to the common normal plane of the heads 9, 9 of the fingers of the group A, with eyes 19, 19 of said bracket 17 (see Fig. 1) respectively aligned with the eyes 11, 11 of said heads 9.

The various yarns a, b, c, d and e (see Fig. 11), pass from suitable supply packages, not shown, through the eyes 19 in the guide bracket 17, to 15 and through the eyes 11 in the control fingers 1, 2, etc. to the main clamp B and temporary clamp C or to the running eye E, as the case may be.

The gears 14, 14 of the control fingers 1, 2, 3, 20 4 and 5 respectively, are adapted to be selectively brought into operating alignment with an operating gear 20 (see Figs. 5, 7 and 10), which is secured to one end of a sleeve shaft 21. The sleeve shaft 21 is rotatably mounted on a horizontal stud 22, fixed in and extending laterally from one side of a vertical portion 23 of the main frame F of the device.

The opposite end of the sleeve shaft 21 is provided with a gear 24, fixed thereto, which meshes 30 with a gear 25. The gear 25 is secured to one end of a shaft 26 which is rotatably mounted in the frame F. The gear 25 has one set of teeth 25a formed on one pitch circle, for meshing with the teeth of the gear 24, and a second set of 35 teeth 25b formed on a different pitch circle and which are adapted to mesh with the teeth of a vertical gear rack 27 (see Fig. 3).

The gear rack 27 is vertically slidably mounted in a guideway 28 formed in the vertical part 40 23 of the frame F, so that, upon vertical movement of the rack 27 one of the fingers 1, 2, 3, 4 or 5, as the case may be, depending upon the selection made by the pattern mechanism of the machine to which the device is secured, will be 45 operated, through the gears 25, 24, 20 and 14, to swing the finger of the selected yarn from its normal position shown in Fig. 11 to its operating position shown in Fig. 12.

The finger to be operated is selected by sliding 50 the whole group A bodily, laterally to the right as viewed in Fig. 5, to bring the gears 14, 14 of the fingers 1, 2, 3, 4 and 5 successively into operating alignment with the operating gear 20.

The gear 14 of the finger 1, controlling the 55 yarn a is normally in operating alignment and intermeshing with the operating gear 20, while the teeth of the gears 14 of the other fingers are normally in intermeshing engagement with the teeth of a fixed locking gear member 30 in 60 the form of a gear rack or gear segment (see Fig. 9), which keeps these fingers from rotating, normally.

As the group A of control fingers slides along horizontally during the selecting operation, the teeth of the gears 14 slide along the teeth of the fixed gear member 30, from one side of the operating gear 20, into mesh with the teeth of the operating gear 20 and from there into relocking engagement with the teeth of an additional 70 fixed gear member 31 disposed at the opposite side of the operating gear 20, until the selection is made by the group A stopping with the gear 14 of the selected finger in operating alignment with the gear 20.

The locking gear members 30 and 31 are formed on or carried by a common element 32 which is provided with a rearwardly extending lug 33 bored at 34 to fit the fixed stud 22 to which the locking element 32 is secured by set screw 35. As shown in Fig. 9 the locking element 32 is provided with a recess 36 into which the operating gear 20 projects. The teeth of the gear members 30 and 31 of the locking element 32 are preferably formed on a pitch circle corresponding to that of the operating gear 20, and, during the selecting operation, certain of the teeth of the operating gear 20 are in alignment with one or more of the teeth of each of the gear members 30 and 31 and combine therewith to provide continuous surfaces against which the teeth of the gears 14, 14 rest during the sliding motion of the group of fingers A. Accurate alignment of the teeth of the actuating gear 20 with the teeth of the locking members 30 and 31 is afforded by a lug 27a on the rack 27 engaging a stop 23a on the vertical portion 23 of the frame F. The concave recesses 8 in the hub discs 6 of the fingers 1, 2, 3, 4 and 5 respectively provide the necessary clearance for the teeth of the gear 20 and locking members 30 and 31 during the sliding of the group of fingers A relative thereto.

In order to effect the sliding selecting movement of the group of fingers A, the stud 16 on which said fingers of the group A are pivotally mounted constitutes an axial extension of a slide bar 40, which is slidably mounted in the framework F. At the end opposite the group of fingers A, the slide bar 40 is provided with a lateral extension 41. The outer end of the extension 41 is provided with a pin 42 (see Figs. 1 and 5) which slides in a slot 43 formed in a guide plate 44 secured to the frame F.

The pin 42 projects into a cam slot 45 formed in a cam plate 46 which is pivoted on a bolt 47 tapped into the vertical portion 43 of the frame F. The cam plate 46 is provided with a hub 48 around which is coiled a spring 49. One end of the spring 49 engages a lug 50 on the cam plate 46 while the second end of the spring is anchored in a flange 51 formed on or keyed to the pivot bolt 47. The spring 49 at all times tends to turn the cam plate 46 in the direction of the arrow z, Fig. 1, to slide the bar 40 and the group of fingers A to the left, as shown in said figure, until the gear 14 associated with the finger 1 is in operating alignment with the operating gear 20.

The cam plate 46 is rotated in the opposite direction by the pattern mechanism of the knitting machine, for example, to which the device is attached, said pattern mechanism being clearly illustrated and described in the aforesaid prior patents. The pattern mechanism includes a pattern chain having links of various heights, a different height for each of the five fingers in the present instance. The pattern links are brought to bear against a lever which is connected by a link 52 to a lever 53, which, in the present instance, is pivotally mounted at 54 to a fixed part of the machine or to an extension of the frame F. The lever 53 is connected by a link 55 to a stud 56 axially aligned with and projecting outwardly from the end of the lug 50 on the cam plate 46.

As the link 52 is moved in the direction of the arrow y, Fig. 1, by one of the links of the pattern chain previously noted, the lever 53 is rocked about its pivot 54 and, through the link 55, rocks the cam plate 46 about its pivot 47,

thereby causing the cam slot 45 to move relative to the pin 42 on the slide bar 40, which in turn effects sliding motion of the bar 40 and the group of fingers A carried thereby until the selected finger is in alignment with the operating gear 20. 5

As shown in Fig. 1 the cam groove 45 is arranged in five steps, indicated at 45a, 45b, 45c, 45d and 45e at successively greater distances from the center of the bolt 47 about which the cam plate 46 revolves, and progressively circumferentially of the cam plate, the steps 45a, b, c, etc., corresponding to the fingers 1, 2, 3, 4 and 5 which control the threads or yarns a, b, c, d and e respectively.

Rockably mounted on the pivot stud 54 is a lever 60 to which is connected one end of a reach rod 61 having an eccentric strap 62 secured to its opposite end. The eccentric strap 62 encircles an eccentric 63 which is secured to a constantly rotating shaft 64 and by which the lever 60 is constantly oscillated on the stud 54. Loosely mounted on the stud 54 is a lever 65 which is connected by a link 66 to the lower end of the operating rack 27. Pivoted at 67 to the lever 65 is a pawl 68, the tip of which normally bears against an elevated surface 69 of a hold-out cam 70. The hold-out cam 70 is rockably mounted on the stud 54 and is provided with an arm 71 which is connected at 72 to one end of a link 73. The opposite end of the link 73 is connected at 74 to the cam plate 46.

When the cam plate 46 is rocked about its pivot, in making a selection as previously noted, it rocks the hold-out cam 70 about the pivot stud 54, moving the elevated portion 69 of the cam 70 from beneath the tip of the pawl 68, whereby the tip of the pawl 68, under the influence of a spring 75, rides down onto a lower portion 76 of the cam 70 into the path of a shoulder 77 formed on the outer end of a lever 78 which is secured to the lever 68 and is constantly rocked therewith about the pivot stud 54 by the eccentric 63 through the eccentric strap 62 and reach rod 61.

With the tip of the pawl 68 lying in the path 45 of movement of the shoulder 77 on the lever 78, when the lever 78 rocks in the direction of the arrow x, the shoulder 77 engages the pawl 68 and rocks the lever 65 about the pivot stud 54. Rocking of the lever 65 in this manner 50 causes a vertical movement of the gear rack 27, through the link 66. The rack 27, being in engagement with the gear 25, rotates said gear about the stud 26. The gear 24, being in mesh with the gear 25, is consequently rotated and 55 through the sleeve shaft 21 rotates the operating gear 20 and consequently the gear 14 of the yarn control finger which has been selectively moved into operating alignment with the gear 20. The selected finger is consequently rocked 60 about the pivot 16 from the normal position shown in Fig. 11 to the operative position shown in Fig. 12.

As the selected finger rocks in the manner noted, it carries the selected yarn controlled 65 thereby upwardly, drawing the selected thread through the guide eye 19 in the guide bracket 17 and thereby elongating the portion a1, b1, c1, d1, e1, as the case may be, which extends from the eye 19 in the guide bracket 17 to the eye 11 70 in the end of the selected control finger. During the rocking movement of the selected finger the prong or barb 12 intermediate the opposite ends thereof engages the elongated portion of the selected yarn, as indicated at c1 in Fig. 12, and 75

maintains said portion of the yarn in a predetermined position for purposes hereinafter noted.

As shown in Fig. 11 the free end portions *a2*, *b2*, *c2*, *d2*, *e2* of the yarns *a*, *b*, *c*, *d*, and *e* respectively which are idle, project from the guide eyes *11* in the yarn control fingers to the main clamp *B*. As shown in Figs. 22, 23, 24 and 25 the main clamp *B* comprises plates *80*, *81*, *82* and *83* respectively which are arranged in superposed relation to each other with the plate *80* lowermost, as shown in Fig. 6. The uppermost plate *83* is provided with an elongated slot *84* for the reception of a correspondingly shaped projection *85* on the lower end of the vertical shaft *86* of the 15 knotting device *K*.

A relatively thick circular disc *87* is secured firmly to and in contact with the lower surface of the projection *85* and the under-surface of the plate *83* by a screw *88*, tapped into the lower 20 end of the shaft *86*. Each of the plates *80*, *81* and *82* is provided with circular opening *89* through which the disc *87* projects. A star-shaped concavo-convex spring *90* bearing against the under surface of the plates *81* maintains the 25 plates *80*, *81*, *82* and *83* in firm but resilient contact one with the other.

As shown in Fig. 16, screws or pins *91*, *91*, secured in and projecting downwardly from a horizontal plate portion *92* of the frame *F*, project 30 through openings *93* and *94* in the plates *80* and *82* respectively, to prevent said plates *80* and *82* from rotating with the plate *83* when the shaft *86* of the knotter *K* is turned in a manner hereinafter noted.

35 A pin *95* is secured to the plate *83* and projects downwardly therefrom through arcuate slots *96*, *97* and *98* in the plates *80*, *81* and *82* respectively.

The slot *97* in the plate *81* is relatively short but of greater length than the diameter of the 40 pin *95*, and the ends *97a* and *97b* of said slot are alternately engaged by the pin *95* after the plate *83* rotates through a small portion of its complete oscillatory motion in clamping and releasing the free ends of the various yarns in the manner 45 hereinafter described.

The main fixed clamp plate *80* is provided with a yarn channel *99* through which the free ends of the idle yarns extend upwardly. Adjacent the 50 terminal end of the yarn channel *99* the upper surface of the fixed clamp plate *80* is provided with serrations *100*. The edges *101*, *102* at the opposite end of the channel *99* flare outwardly to receive the yarns, and a shoulder *103* is formed at the mouth to prevent the yarns from being 55 forced out of the channel *99* under circumstances hereinafter noted.

The main rotary clamp plate *81* is provided with a hook-like projection *104*, which, as the plate *81* rocks in one direction about the axis of the shaft *86*, sweeps along and above the channel *99* and engages the threads projecting upwardly therethrough. The forward edge *105* of the hook *104* carries the threads across the serrations *100*, whereby the ends of the idle threads 60 are firmly gripped between the serrations *100* on the fixed plate *80* and the movable plate *81*.

The upper fixed plate *82* is provided with a hook-shaped arm *106* between the inner curved 70 edge *107* of which, and the opposite curved edge *108* of the main body of the plate *82*, a yarn channel *109* is formed with a shoulder *110* at the open flaring mouth of the channel.

The upper movable plate *83* is provided with 75 a hook *112*, similar to the hook *104* of the lower

movable clamp plate *81*, with a yarn engaging edge *113* thereon.

The temporary clamp *C*, shown detached in Fig. 26, includes a main fixed plate *115*, which lies below the fixed plate *80* of the main clamp *B* 5 (see Fig. 6) and is provided with an opening *116* for reception of a reduced boss *117* on the thick disc *87*; and a second opening for reception of the screw *91* by which the plates *80*, *82* and *115* are held against rotation about the axis of the 10 knotter shaft *86*.

The head *119* of the screw *88* retains the plate *115* against dropping and the star spring resting on the plate *115* presses the plates *80*, *81* and *82* upwardly into resilient contact with each other 15 and with the top plate *83* of the main clamp *B*.

The fixed plate *115* is provided with an arm *118* having an upstanding projection *119* adjacent the outer end thereof (see Fig. 26). Pivotal- 20 ly mounted on a pin *120* secured in and projecting vertically from the arm *118*, is a lever *121* which forms the movable element of the temporary clamp *C*.

The clamp *C* has a yarn channel *122* formed therein between one edge *123* of the lever *122* 25 and an upturned flange *124* formed on an adjacent opposite edge of the fixed plate *115*. The channel *122* has an outwardly flaring mouth formed between the angular edge *125* of the lever *121* and the angular edge *126* of the plate *115*.

The various threads are adapted to be temporarily gripped during the knotting operation between the edge *123* of the lever *121* and the flange *124* of the plate *115* by rotation of the 35 lever *121* in one direction under the influence of a spring *128* encircling the pin *120*, with one end resting against the projection *119* on the plate *115*, and the other end engaging a U-shaped part of the lever *121*.

The lever *121* has an extension *127* overlying the plate *115* behind the flange *124*, which, under circumstances hereinafter noted, is engaged by the pin *95* of the main clamp plate *83* which rocks the lever *121* in a direction opposite to the influence of the spring *128*, to release the yarns from between the edge *123* and flange *124*. 40

As shown in Fig. 16, the yarn channels *99*, *109* and *122* lie in vertical alignment with the shoulders *103* and *110* and the flaring edges *101*, *111* 50 and *125* substantially coinciding with each other.

The knotter *K* (see Figs. 6, and 17 to 21 inclusive) includes a housing *130* which is secured to the horizontal plate portion *92* of the frame *F*. The housing *130* comprises bearings *131* and *132* for the vertical shaft *86*, and bearings *133* and *134* for the horizontal beak shaft *135* of the knotter which extends through a transverse opening *136* in the shaft *86*, so that the axes of the shafts *86* and *135* can intersect in a common 60 plane at right angles to each other.

Secured to the knotter shaft *86* is a gear *137* which meshes with a pinion *138* on one end of the beak shaft *135*. The opposite end of the shaft *135* is shaped to form the fixed jaw *139* 65 of the beak *140*. The fixed jaw *140* is bifurcated to receive the movable jaw *141* which is pivoted at *142* to the fixed jaw.

The movable jaw *141* is provided with a heel *143* and a toe *144* which ride a cam surface *145* 70 formed on the outer end of the bearing *133* to open and close the beak *140* as it is rotated about the axis of its operating shaft *135*.

Above the beak *140*, the knotter *K* includes a gripper or pincher *150*, which is composed of a 75

pair of blades 151 and 152 (see Fig. 20) which are apertured at 153 to fit the shaft 86 and by which these blades are held against radial movement while permitting oscillatory movement about the axis of the shaft 86.

Intermediate the radially fixed blades 151, 152 the pincher 150 is provided with a radially movable blade 154 (see Fig. 21) which is slotted longitudinally at 154a to receive the shaft 86.

10 The blades 151, 152 and 154 are maintained in parallel relatively slidable relation to each other by a pair of parallel arms 155, 155 having depending ends 156, 156 (see Fig. 19), with a slot 157 therebetween, said depending ends being 15 shouldered at 158 to bear against the upper blade 151 to prevent upward movement thereof, downward movement being prevented by the lower blade 152 resting on the top of the body portion 159 of the gear 137 (see Fig. 6).

20 The guide arms 155, 155 are integrally formed with a hub 160 having a bore 161 to fit and rotate about the exterior surface of the upper bearing 132 for the knotter shaft 86.

The blades 151 and 152 are transversely slotted 25 to form a yarn channel 162 and the outer end 163 of the blade 154 is adapted to cooperate with the edges 164, 164 of the channel 162 to pinch the running yarn and the newly selected yarn therebetween during the knotting operation, as 30 hereinafter described.

The blade 154 is provided with an upstanding pin 154b (see Fig. 21) which operates in a cam slot 166 formed in a cam plate 167 secured to the frame 130 of the knotting device K (see Fig. 35 5).

Secured to the top of the frame 130 at 168, is a cam plate 169 which is provided with a cam slot 170 (see Fig. 18). A pin 171 secured to one 40 end of a lever 172 operates in the cam slot 170. The lever 172 is provided with a second pin 173 which operates in the slot 157 between the guide arms 155, 155 of the pincher 150 (see Fig. 17). Intermediate the pins 171 and 173, the lever 172 is pivoted at 174 to the operating lever 175 for 45 the knotter shaft 86 (see Fig. 4), and in which the running eye E is also formed.

The cam slot 170 is so formed that, as the lever 175 is rocked in one direction, the pivot 174 for the lever 172 is carried along on a predetermined arc about the axis of the knotter 86. The lever 172 is correspondingly moved and the pin 171 traverses the cam slot 170. The pin 173 on the lever 172 riding in the forked guide lever 155, 155 of the pincher 150 rotates the pincher 55 bodily about the axis of the shaft 86, until the pin 171 rides into a dwell portion 176 of the cam slot 170. This causes the pincher to stop momentarily as the beak 140 of the knotter rotates and effects the tying of a knot between the running yarn and the newly selected yarn, after which the pincher continues on its circular movement relative to the beak of the knotter to pull the knot tight, as a result of the involved yarns being held tightly at one side of the knot by the beak 140 at the opposite side of the knot by the pincher 150.

It will be understood that the above action takes place after the running yarn and the newly selected yarn have been placed in the beak 140 and in the channel 162 of the pincher; and that the movable blade 154 of the pincher has advanced radially to pinch these yarns against the edges 164, 164 of the blades 151 and 152 respectively, by the pin 154b on the blade 154 running in the cam slot 166.

After the new yarn selection has been made, as previously described, but before the control finger of the selected yarn moves from the position shown in Fig. 11, to the position shown in Fig. 12, the portions *a*2, *b*2, *c*2, *d*2 and *e*2 of the 5 yarns *a*, *b*, *c*, *d* and *e* respectively, i. e. the portions lying between the clamp B and the eyes 11, 11 of the fingers 1, 2, 3, 4 and 5 respectively, are within the embrace of a sweep arm 180 (see Fig. 11). As the finger of the newly selected 10 yarn moves from the position shown in Fig. 11 to that shown in Fig. 12, the sweep arm moves in a circular path in a horizontal plane below the temporary clamp C and main clamp B and gathers in the running yarn, for example, the 15 portion *a*2 of the running yarn *a*, as shown in Fig. 11, and moves it into the channel 122 of the temporary clamp C, the channel 99 of the main clamp B, and the channel 109 of the auxiliary to the main clamp formed by the plates 82 and 83. 20

The control finger of the newly selected yarn, for example, during the gathering in of the portion *a*2 of the running yarn *a*, has moved into its position shown in Fig. 12. During its movement from the position in Fig. 11 to its position 25 in Fig. 12, the barb 12 on the finger 3 has picked up the portion *c*1 of the yarn *c* and held it out of reach of the sweep arm 180 so that it would not be delivered into the clamp channels noted above with the portions *a*2, *b*2, *c*2, *d*2 and *e*2 of the 30 yarns *a*, *b*, *c*, *d* and *e*.

In the meantime, the portion *c*2 of the selected yarn *c*, and the portion *a*2 of the running yarn *a* have been carried by the finger 3 into the throat of the beak 140 and the open pincher 150, 35 as shown in Fig. 12.

The knotter shaft 86 is then operated to rotate the beak 140 and cause the pincher 150 to move the two yarns forwardly (see Fig. 13). As the shaft 86 rotates to effect this motion the pin 95 40 on the plate 83 moves away from the arm 127 of the temporary clamp C and the spring 128 rocks the lever 121 to cause the edge 123 thereof to grip the running yarn *a* against the flange 124 of the fixed plate 115. 45

At the same time the pin 154b operating in the cam slot 166 moves the blade 154 outwardly to grip the two yarns *a* and *c* in the pincher 150.

The above noted rotation of the shaft 86 turns the beak shaft 135 and the beak 140 therewith. 50 The heel and toe of the rockable jaw 141 of the beak 140 riding on the cam 145 closes the jaws of the beak as the loop L of the knot is formed around the rotating beak, just after the elements assume the positions shown in Fig. 14. 55

As the jaws of the beak close on and grip the two yarn portions *a*2 and *c*2, the two yarns are severed below the beak 140 by a revolving shear S and the ends of the two yarns are drawn through the loop L. 60

At the same time, with the beak revolving rearwardly over the top, as viewed in Fig. 14, the pincher 150, which is still gripping the yarn portions *a*2, *c*2, above the loop L, moves forwardly and pulls the loop off the beak and then pulls 65 the loop into a tight knot.

The beak 140 and the pincher 150 are then opened to release the yarns and the newly selected yarn *c* tied to the former running yarn *a* supplants the yarn *a* as the running yarn. 70

The finger 3, then returns to its normal position and the spring 49 (see Fig. 1) returns the cam plate 46 to shift the entire group A of fingers 1, 2, 3, 4, 5 until the gear 14 of the finger 1 is again aligned with the operating gear 20. 75

The roller on the lever to which the link 52 is attached in the meantime has ridden off the link of the pattern chain which had selected the yarn c. The cam surface 69 has also dislodged the pawl 68 from the shoulder 71 of the power lever 78 and a lug 78a on this lever has engaged a set screw 65a on the lever 65 to move the rack 27 downwardly under positive motion to return the finger 3 to its normal position with the newly selected yarn c running from the eye 11 of the finger 3 to the eye E in the actuating lever 175 of the knotter K.

The sweep arm 180 has moved to its outer position shown in Fig. 12 and as the finger 3 returns to its normal position the new running yarn c is guided into the arc of embrace of the sweep arm 180 by a fixed guide wire 181 secured at one end to the platform 92 of the frame F.

The sweep arm 180 is pivoted at 182 to the underside of the platform 92 and is provided with a radial slot 183 (see Fig. 5). The slot 183 embraces a pin 184 (see also Fig. 7) which projects upwardly from a bracket 185 which is secured to a horizontal rod 186. The rod 186 is slidably mounted in the vertical extension 23 of the frame F and is provided with a pin 187 riding in a cam slot 188 formed in a curved cam plate 189 secured to the gear 25. The gear 25 is provided with an arcuate slot 191 through which the rod 186 passes.

The actuating lever 175 of the knotter K is operated by a lever 192, which is secured to a vertical shaft 193, through a pin 194 on the lever 175 operating in a slot 195 formed in the lever 192.

The upper end of the shaft 193 is journaled in a bearing 196 formed on or carried by the frame F, and at its lower end in a bearing formed in the base plate 200 of the machine to which the frame F is secured.

Below the bed plate 200 the shaft 193 is provided with a horizontal lever 201 (see Fig. 1 and Fig. 1a). The outer end of the lever 201 has a roller 202 thereon for contact by a cam 203 for 45 rocking the lever 201 in one direction and a cam 204 for rocking the lever in the opposite direction to oscillate the shaft 193 and the knotter shaft 86 to effect operation of the knotter K in the manner previously described.

50 The cams 203 and 204 (see Fig. 3) are secured to the constantly rotating shaft 64 on which is also secured the eccentric 63, as previously noted. To prevent actuation of the shaft 193, except at the time a selection of yarns and the knotting operation is taking place, the shaft 193 (see Fig. 27) is provided with a collar 205 which is engaged on its under side by the outer end of a short arm 206. The arm 206 is secured to the shaft 26 on which the gear 25 is also secured. 55 Consequently, when the gear 25 is turned in one direction to actuate one of the fingers 1, 2, 3, 4 or 5, the arm 206 is turned to lower the shaft 193, and the lever 201, under the action of a spring 207 (see Fig. 1) to drop the roller 202 of the lever 60 201 into the paths of rotation of the cams 203 and 204 to operate the knotter K.

When the gear 25 is turned in the opposite direction to return the finger 1, 2, 3, 4 or 5 as the case may be, to its normal position, the arm 70 206, operating against the underside of the collar 205, raises the roller 202 out of the paths of rotation of the cams 203 and 204.

The shear S (see Figs. 4, 14 and 15) comprises an upper blade 210 which revolves on a stud 211 75 projecting upwardly from the platform 92 (see

Fig. 3), and a blade 212 which is pivoted at 213 to the blade 210. The blade 212 is provided with a roller 214 (see Fig. 15) which rides in a cam groove 215 formed in a disc 216 which is secured to the platform 92. 5

A pinion 217 is secured to the blade 210 (see Figs. 3 and 4) and intermeshes with a gear segment 218 which oscillates on a post 219 projecting upwardly from the platform 92. Screws 220, 220 carried by the segment 218 and adapted to 10 engage a post 221 limit the rocking motion of the segment 218 and consequently the rotation of the shear blades 210 and 212 relative to the cam disc 216.

A link 222 pivotally connected at 223 to the 15 knotter operating lever 175 and at 224 to the segment 218 effects operation of the shear S in coordination with the knotter K as noted above. As the pinion 217 rotates the constant blade 210 and the movable blade 212, the roller 214 operating in the groove 215 rocks the blade 212 at the proper time to snap the two yarns gripped by the beak 140 just before the beak pulls the gripped parts of the two yarns through the loop L. 20

After the sweep arm 180 has carried the running 25 yarn into the yarn channels 122, 99 and 109, and the control finger of the newly selected yarn moves from the position shown in Fig. 11 to that shown in Fig. 12 wherein the part c2 of the newly selected yarn extends upwardly from the clamp B 30 to the eye 11, substantially parallel to the part a2 of the running yarn, the shaft 86 of the knotter K begins to turn in the direction of the arrow y (see Fig. 16). The plate 83 turns correspondingly, causing the pin 95 to release the lever 35 121 of the temporary clamp C. The pin 95 then engages the end 97b of the plate 81 of the main clamp B, turning this plate and releasing the idle yarns from the serrations 100 of the fixed clamp plate 80. At the same time the back edges 40 80a and 81a of the main clamp and the auxiliary clamp, the latter being formed by the plates 82 and 83, move outwardly against the running thread, which has just been placed in the above noted channels by the sweep arm 180, and the 45 part of the newly selected yarn which has been raised by its control finger. This action causes these yarns to be pressed against the arm 106 of the fixed plate and to be snubbed around the edge 107 of the arm 106, to apply a holding force to 50 these yarns, in addition to the grip of the temporary clamp C, while the beak 140 is forming the loop L.

The plates 83 and 82 continue to move outwardly and force the two yarns against the shoulders 103 and 110 of the fixed plates 80 and 82 respectively. The two yarns then snap around the ends of the hooks 104 and 112 of the plates 81 and 83 respectively into the fronts of said hooks to be 55 engaged by the curved edges 105 and 113 thereof, 60 upon reverse rotation of the shaft 86.

The shear S, during the above action, has cut the former running yarn and that part of the newly selected yarn which had been carried up by the control finger, at the knot. This leaves a 65 loose piece of the newly selected yarn, which is wiped away from the clamps etc. by the plate 83, as the shaft 86 moves in said reverse motion of the shaft 86.

As the plate 83 receives its motion, by said reverse motion of the shaft 86, the pin 95 thereon engages the end 97a of the clamp plate 81, causing the forward edge 105 of the hook 104 to wipe the ends of the idle threads, including the former 70 75

running yarn, over the serrations 100 of the fixed plate 80.

As the plate 83 approaches the limit of its motion under said reverse rotation of the shaft 86 the pin 95 engages the arm 121 of the temporary clamp C and releases the grip of said clamp C from the idle threads in the channel 122 (see Fig. 16).

The device is then ready for a new selection 10 of yarn by one of the high links of the pattern chain which controls the actuation of the link 52 (Fig. 1) and consequently the selector cam 46.

It will be noted that each of the steps 45a, 45b, 15 45c, 45d and 45e in the cam slot 45 of the cam 46 includes a dwell space 45', concentric to the axis 20 of rotation of the cam 46 which prevents sliding motion of the group A of fingers by vibration of the machine which might cause the cam 46 to oscillate slightly while holding the gear 14 of a selected finger in mesh with the operating gear 20.

It will be further noted that the yarn channel 99 of the main clamp B, the yarn channel 122 of the temporary clamp C, the yarn channel 164 of the pincher 150, the throat 165 of the knotted beak 140, the running yarn guide E, and the operating gear 20 for the fingers 1, 2, 3, 4 and 5, lie substantially in a common vertical plane P—P (see Figs. 1, 4, 5, 16); that the arc traversed by the bite of the open shear blades 210, 212 is substantially tangent to said plane P—P; that the steps 45a, 45b, 45c, 45d and 45e of the cam plate 46 move the group A of fingers 1, 2, 3, 4 and 5, bodily, axially of their common pivot 16, variable distances respectively, to bring the gears 14 of said fingers, and the fingers, selectively into the plane P—P, to effect operating alignment of the gear 14 of the selected finger 1, 2, 3, 4, 5, as the case may be, with the operating gear 20 which rotates in the plane P—P; and that the selected finger, with its eye 11 and collector notch 10, when actuated by the single actuating gear 20, rocks in the plane P—P to carry the selected yarn and the running yarn into the above noted channels in the plane P—P.

I claim:

1. A yarn changer comprising a group of yarn-control elements arranged side by side, a single actuator for operating a single element of said group, and means for laterally shifting said group bodily with respect to said actuator to effect selective alignment of a single element of the group with said actuator.

2. A yarn changer comprising a group of yarn-control elements arranged side by side, a single actuator for operating a single element of said group, means for laterally shifting said group bodily with respect to said actuator to effect selective alignment of a single element of the group with said actuator, and means for locking said group of elements against independent operation during said bodily shifting of the group.

3. A yarn changer comprising a group of yarn-control elements arranged side by side, a single actuator for operating a single element of said group, means for laterally shifting said group bodily with respect to said actuator to effect selective alignment of a single element of the group with said actuator, means for operating said actuator to effect independent yarn manipulating motion of the element aligned with said actuator, and means for locking the remaining elements of the group against yarn manipulating motion during said independent manipulating motion of the single selected element.

4. A yarn changer comprising a group of yarn-control elements arranged side by side, a single actuator for operating a single element of said group, means for laterally shifting said group bodily with respect to said actuator to effect selective alignment of a single element of the group with said actuator, a clamp provided with a channel for receiving yarns extending from eyes in said elements respectively, and a sweep arm adapted to embrace and carry 10 said extending yarns into said clamp channel.

5. A yarn changer comprising a group of yarn-control elements arranged side by side, a single actuator for operating a single element of said group, means for laterally shifting said 15 group to effect selective alignment of a single element of the group with said actuator, a clamp provided with a channel for receiving yarns extending from yarn eyes on said elements respectively, a yarn guiding eye for passage of the yarn from the yarn eye of one of said elements which is free from said clamp, a sweep arm adapted to embrace said free yarn and carry it into said channel, a yarn collector 20 on each of said elements for engaging said free yarn between said yarn guiding eye and said clamp channel, a knot tying device having a 25 yarn throat between said clamp channel and the path of movement of the yarn collector and yarn eye of the selected element for receiving said free yarn and the yarn controlled by said selected element, and means for operating said selected element through said actuator.

6. A yarn changer comprising a group of 35 yarn-control elements arranged side by side, a single actuator for operating a single element of said group, means for laterally shifting said group to effect selective alignment of a single element of the group with said actuator, a clamp provided with a channel for receiving yarns 40 extending from yarn eyes on said elements respectively, a yarn guiding eye for passage of the yarn from the yarn eye of one of said elements which is free from said clamp, a sweep arm adapted to embrace said free yarn and carry it into said channel, a yarn collector on each of said elements for engaging said free yarn between said yarn guiding eye and said clamp channel, a knot tying device having a 45 yarn throat between said clamp channel and the path of movement of the yarn collector and yarn eye of the selected element for receiving said free yarn and the yarn controlled by said selected element, a yarn pincher operable between said 50 throat and said yarn guiding eye for receiving said free and selected yarns, means for operating said knot tying device and said pincher, and means for operating said selected element through said actuator.

7. A yarn changer comprising a group of 55 yarn-control elements arranged side by side, a single actuator for operating a single element of said group, means for laterally shifting said group to effect selective alignment of a single 60 element of the group with said actuator, a clamp provided with a channel for receiving yarns extending from yarn eyes on said elements respectively, a yarn guiding eye for passage of the yarn from the yarn eye of one of said elements 65 which is free from said clamp, a sweep arm adapted to embrace said free yarn and carry it into said channel, a yarn collector on each of said elements for engaging said free yarn between said yarn guiding eye and said clamp 70 clamp 75

channel, a knot tying device having a yarn throat between said clamp channel and the path of movement of the yarn collector and yarn eye of the selected element for receiving said free 5 yarn and the yarn controlled by said selected element, a yarn pincher operable between said throat and said yarn guiding eye for receiving said free and selected yarns, a shear operating between said knot tying device and said clamp 10 for severing said free and selected yarns adjacent said knot tying device subsequent to knotting the two yarns together, means for operating said knot tying device, said pincher, said clamp and said shear, and means for operating said selected element through said actuator in timed relation one to the other.

8. A yarn changer comprising a group of yarn control elements arranged side by side, a yarn clamp provided with a yarn receiving channel, 20 a yarn guiding eye spaced from said clamp substantially in a common plane with the yarn receiving mouth of said channel, a yarn knitter including a knotting beak having a throat substantially in said common plane intermediate 25 said eye and said channel mouth, a yarn eye on each control element, a yarn collector on each control element adjacent the yarn eye thereof, means for bodily shifting said group laterally and with respect to said common plane 30 for selectively aligning the yarn eye and yarn collector of one of said elements with said common plane, and means for operating the selected element with its yarn eye and yarn collector moving in said common plane to carry a predetermined pair of yarns respectively controlled by said elements into said throat.

9. A yarn changer comprising a group of yarn control elements arranged side by side, a yarn clamp provided with a yarn receiving channel, 40 a yarn guiding eye spaced from said clamp substantially in a common plane with the yarn receiving mouth of said channel, a yarn knitter including a knotting beak having a throat substantially in said common plane intermediate 45 said eye and said channel mouth, a yarn eye on each control element, a yarn collector on each control element adjacent the yarn eye thereof, means for bodily shifting said group laterally and with respect to said common plane for selectively aligning the yarn eye and yarn collector of one of said elements with said common plane, means for operating the selected element with its yarn eye and yarn collector moving in said common plane to carry a predetermined pair of yarns respectively controlled by said elements into said throat, and a sweep arm operable in a plane intersecting said common plane in advance of said operation of said 50 selected yarn control element for moving one yarn of said pair into the channel of said clamp prior to knotting.

10. A yarn changer comprising a group of yarn control elements arranged side by side, a yarn clamp provided with a yarn receiving channel, 65 a yarn guiding eye spaced from said clamp substantially in a common plane with the yarn receiving mouth of said channel, a yarn knitter including a knotting beak having a throat substantially in said common plane intermediate 70 said eye and said channel mouth, a yarn pincher intermediate said yarn guiding eye and said knotting beak and having a yarn channel in said common plane, a yarn eye on each control element, a yarn collector on each control element

adjacent the yarn eye thereof, means for bodily shifting said group laterally and with respect to said common plane for selectively aligning the yarn eye and yarn collector of one of said elements with said common plane, and means for operating the selected element with its yarn eye and yarn collector moving in said common plane to carry a predetermined pair of yarns respectively controlled by said elements into said throat and into said channel of said pincher. 10

11. A yarn changer comprising a group of yarn control elements arranged side by side, a yarn clamp provided with a yarn receiving channel, a yarn guiding eye spaced from said clamp substantially in a common plane with the yarn 15 receiving mouth of said channel, a yarn knitter including a knotting beak having a throat substantially in said common plane intermediate said eye and said channel mouth, a yarn pincher intermediate said yarn guiding eye and said knotting beak and having a yarn channel in said common plane, a yarn eye on each control element, a yarn collector on each control element adjacent the yarn eye thereof, means for bodily shifting said group laterally and with respect to said common plane for selectively aligning the yarn eye and yarn collector of one of said elements with said common plane, means for operating the selected element with its yarn eye and yarn collector moving in said common plane 20 to carry a predetermined pair of yarns respectively controlled by said elements into said throat and into said channel of said pincher, and a sweep arm operable in a plane intersecting said common plane in advance of said operation of said selected yarn control element for moving one yarn of said pair into the channel of said clamp prior to knotting. 25

12. A yarn changer comprising a group of yarn control elements arranged side by side, a yarn clamp provided with a yarn receiving channel, a yarn guiding eye spaced from said clamp substantially in a common plane with the yarn receiving mouth of said channel, a yarn knitter including a knotting beak having a throat substantially in said common plane intermediate 45 said eye and said channel mouth, a yarn eye on each control element, a yarn collector on each control element adjacent the yarn eye thereof, means for bodily shifting said group laterally and with respect to said common plane for selectively aligning the yarn eye and yarn collector of one of said elements with said common plane, means for operating the selected element with its yarn eye and yarn collector moving in said common plane to carry a predetermined pair of yarns respectively controlled by said elements into said throat, a sweep arm operable in a plane intersecting said common plane in advance of 50 said operation of said selected yarn control element for moving one yarn of said pair into the channel of said clamp prior to knotting, and means on each yarn control element remote to the yarn eye and yarn collector thereof for engaging the yarn controlled thereby when selected and operating in said common plane to retain the selected yarn out of reach of said sweep arm. 55

13. A yarn changer comprising a group of yarn control elements arranged side by side, a yarn clamp provided with a yarn receiving channel, a yarn guiding eye spaced from said clamp substantially in a common plane with the yarn receiving mouth of said channel, a yarn knitter including a knotting beak having a throat sub- 75

stantially in said common plane intermediate said eye and said channel mouth, a yarn eye on each control element, a yarn collector on each control element adjacent the yarn eye thereof, a single actuator in said common plane for operating a single element of said group, and means for laterally shifting said group bodily with respect to said plane to effect selective alignment of a single element of the group with said common plane.

14. A yarn changer comprising a group of yarn control elements arranged side by side, a yarn clamp provided with a yarn receiving channel, a yarn guiding eye spaced from said clamp substantially in a common plane with the yarn receiving mouth of said channel, a yarn knotter including a knotting beak having a throat substantially in said common plane intermediate said eye and said channel mouth, a yarn eye on each control element, a yarn collector on each control element adjacent the yarn eye thereof, a single actuator in said common plane for operating a single element of said group, means for laterally shifting said group bodily with respect to said plane to effect selective alignment of a single element of the group with said common plane, and means for operating the aligned element in said common plane through said single actuator aligned therewith.

15. A yarn changer comprising a group of yarn control elements arranged side by side, a common support for said group, a single actuator for a single element of said group, a cam for shifting said common support and said group of elements therewith laterally with respect to said single actuator to effect selective alignment of any single one of said elements with said actuator.

16. A yarn changer comprising a group of yarn control elements arranged side by side, a common support for said group, a single actuator for a single element of said group, a cam for shifting said common support and said group of elements therewith laterally with respect to said single actuator to effect selective alignment of any single one of said elements with said actuator, said cam including a step for each element on the common support and progressively inclining paths from each to the next step to carry said elements successively past said single actuator, a cam follower connected to said common support for engagement with said cam steps and the inclines therebetween, and a dwell at each step affording predetermined motion of the cam without operation of said cam follower and the common support connected thereto.

17. A yarn changer comprising a group of independently swingable yarn control fingers, a common pivot for said group, a single actuator for a single finger of said group, and means for shifting said group bodily to variable extents axially of said pivot to align said fingers selectively with said actuator.

18. A yarn changer comprising a group of arcuate independently swingable yarn control fingers, a hub gear on one end of each finger, a common pivot for the hub gears of the group, an actuating gear adapted to intermesh with one of said hub gears, and means for shifting said group bodily to variable extents axially of said common pivot relative to said actuating gear to align said hub gears selectively with said actuating gear.

19. A yarn changer comprising a group of arcu-

ate independently swingable yarn control fingers, a hub gear on one end of each finger, a common pivot for the hub gears of the group, an actuating gear adapted to intermesh with one of said hub gears, means for shifting said group bodily to variable extents axially of said common pivot relative to said actuating gear to align said hub gears selectively with said actuating gear, and an elongated locking gear member aligned longitudinally with said actuating gear and normally intermeshing with the hub gears of said group unaligned with said actuator gear.

20. A yarn changer comprising a group of arcuate independently swingable yarn control fingers, a hub gear on one end of each finger, a common pivot for the hub gears of the group, an actuating gear adapted to intermesh with one of said hub gears, means for shifting said group bodily to variable extents axially of said common pivot relative to said actuating gear to align said hub gears selectively with said actuating gear, and an elongated locking gear member at each end of and aligned longitudinally with said actuating gear and adapted to intermesh with the hub gears of said group unaligned with said actuator gear.

21. A yarn changer comprising a group of arcuate independently swingable yarn control fingers each including a pivot at one end and a yarn eye adjacent said collector, means for swinging said fingers selectively about their respective pivots, a yarn channel for receiving yarns passing through said yarn eyes respectively, and a sweep arm operable in a plane intersecting the paths of swing of said fingers for presenting said yarns to said channel.

22. A yarn changer comprising a group of arcuate independently swingable yarn control fingers each including a pivot at one end and a yarn collector at the opposite end with a yarn eye adjacent said collector, means for swinging said fingers selectively about their respective pivots, a yarn channel for receiving yarns passing through said yarn eyes respectively, a sweep arm operable in a plane intersecting the paths of swing of said fingers for presenting said yarns to said channel, and a lateral projection on each finger intermediate its opposite ends to engage the yarn controlled thereby and hold it out of the path of said sweep arm during swinging motion of said finger.

23. A yarn changer comprising a group of independently swingable yarn control fingers, a common pivot for said group, a group of gears on said common pivot and respectively secured to said fingers, a single actuating gear for co-operation with the gear of a single finger, a sweep arm operable in a plane intersecting the paths of swing of said fingers, means for shifting said group of fingers bodily in a direction axially of said common pivot for effecting selective intermeshing of said finger gears with said single actuating gear, a driving gear for operating said single actuating gear, and a cam on said driving gear for actuating said sweep arm in advance of the selected yarn finger.

24. In a yarn changer, means for knotting two yarns together, shears for cutting said yarns adjacent the knot and comprising a main blade disposed in one plane, a disc disposed in a parallel plane, an auxiliary blade pivoted on said main blade, a cam follower on said auxiliary blade riding in a cam groove in said disc, and means for effecting relative rotary motion be-

tween said main blade and said disc to rock said auxiliary blade on said main blade in a shearing action.

25. In a yarn changer, means for knotting two 5 yarns together, a yarn pincher cooperating with said knotting means for pulling the knot tight, said pincher comprising a pair of blades freely rotatable about a common axis, an intermediate blade freely rotatable about and slidable radially 10 with respect to said axis between said pair of blades, a guide for said three blades freely rotatable about said axis and provided with spaced elements engaging the opposite side edges of said three blades to maintain parallelism therebetween, an actuating arm rockable by power about 15 said axis, a fixed cam adjacent said axis, a lever pivoted intermediate its opposite ends to said actuating arm, a pin on one end of said lever operating in a radial slot in said guide, a cam 20 follower on the opposite end of said lever riding a groove in said cam for producing irregular rotation of said pincher blades about said axis, a pin on said intermediate blade, and a second fixed cam engaging said pin for effecting radial 25 movement of said intermediate blade during said irregular rotation of said pincher.

26. In a yarn changer, means for knotting two 30 yarns of a series together, means for cutting said yarns adjacent the knots, and a clamp for the freed ends of said yarns comprising a series of alternately fixed and rotary parallel plates, an operating shaft secured to one of said rotary plates, a pin on said one rotary plate passing into a short arcuate slot in another of said rotary 35 plates to produce delayed rotation of the latter with respect to initial rotation of the former, and radial extensions on said rotary plates cooperating with predetermined portions on said fixed plates to grip said yarn ends therebetween.

40 27. In a yarn changer, means for knotting two yarns of a series together, means for cutting said 45 yarns adjacent the knots, and a main clamp for the freed ends of said yarns comprising a series of alternately fixed and rotary parallel plates, an operating shaft secured to one of said rotary plates, a pin on said one rotary plate passing into a short arcuate slot in another of said rotary 50 plates to produce delayed rotation of the latter with respect to initial rotation of the former, radial extensions on said rotary plates cooperating with predetermined portions on said fixed plates to grip said yarn ends therebetween, a second clamp comprising a fixed plate and a movable plate pivoted thereto, a projection on said movable plate 55 cooperating with a projection on said fixed plate to grip said yarns therebetween, and an arm on said movable plate operable by said pin to release said secondary clamp during gripping of the yarns by said main clamp.

said pin to release said secondary clamp during gripping of the yarns by said main clamp.

28. In a yarn changer, means for knotting two 5 yarns of a series together, means for cutting said yarns adjacent the knots, and a main clamp for 10 the freed ends of said yarns comprising a series of alternately fixed and rotary parallel plates, an operating shaft secured to one of said rotary plates, a pin on said one rotary plate passing into a short arcuate slot in another of said rotary plates to produce delayed rotation of the latter with respect to initial rotation of the former, 15 yarn channels formed in said stationary plates to receive said yarns, shoulders formed in said channels to prevent escape of said yarns from said channels, radial extensions on said rotary plates movable across said channels to engage said yarns and cooperating with predetermined portions on said fixed plates to grip said 20 yarn ends therebetween, a second clamp comprising a fixed plate and a movable plate pivoted thereto, a projection on said movable plate cooperating with a projection on said fixed plate to grip said yarns therebetween, and an arm on said movable plate operable by said pin to release said secondary clamp during gripping of the 25 yarns by said main clamp.

29. In a yarn changer, means for knotting two 30 yarns of a series together, means for cutting said yarns adjacent the knots, and a main clamp 35 for the freed ends of said yarns comprising a series of alternately fixed and rotary parallel plates, an operating shaft secured to one of said rotary plates, a pin on said one rotary plate passing into a short arcuate slot in another of said rotary plates to produce delayed rotation of the latter with respect to initial rotation of the former, 40 yarn channels formed in said stationary plates to receive said yarns, shoulders formed in said channels to prevent escape of said yarns from said channels, radial extensions on said rotary plates to engage said yarns and cooperating with predetermined portions on said fixed plates to grip said 45 yarn ends therebetween, a second clamp comprising a fixed plate and a movable plate pivoted thereto, a projection on said movable plate cooperating with a projection on said fixed plate to grip said yarns therebetween, and an arm on said movable plate operable by said pin to release 50 said secondary clamp during gripping of the yarns by said main clamp, said projections when separated to release said yarns forming a channel to receive said yarns in alignment with the yarn channels of said main clamp.

55 WALTER LARKIN.
